Application September 24, 1953, Serial No. 26,946

Term of patent 14 years

(Cl. D9—2)

To all whom it may concern:

Be it known that I, Coleman Morse, have invented a new, original, and ornamental Design for a Folding Toothbrush, of which the following is a specification, reference being had to the accompanying drawing, forming a part thereof.

Fig. 1 is a front elevational view of the toothbrush in folded position;

Fig. 2 is a side elevational view;

Fig. 3 is a rear elevational view;

Fig. 4 is a top view;

Fig. 5 is a front elevational view showing the device in open position; and

Fig. 6 is a side view in open position.

The dominant features of my design reside in those parts shown in full lines.

I claim:

The ornamental design for a folding toothbrush, as shown and described.
